US00D693342S

(12) **United States Design Patent**
Sip et al.

(10) **Patent No.:** US D693,342 S
(45) **Date of Patent:** ** Nov. 12, 2013

(54) **EXTERNAL ELECTRONIC DEVICE**

(75) Inventors: **Kim Yeung Sip**, Taipei Hsien (TW);
Wei-Yuan Cheng, Taipei Hsien (TW);
Hao-Sheng Lo, Taipei Hsien (TW)

(73) Assignee: **Acer Incorporated**, Taipei Hsien (TW)

(**) Term: **14 Years**

(21) Appl. No.: **29/406,146**

(22) Filed: **Nov. 10, 2011**

(30) **Foreign Application Priority Data**

Sep. 7, 2011 (TW) 100304695

(51) **LOC (9) Cl.** **14-02**

(52) **U.S. Cl.**

USPC **D14/358**

(57) **CLAIM**

The ornamental design for external electronic device, as shown and described.

DESCRIPTION

FIG. 1 is a front perspective view thereof;

FIG. 2 is a front view thereof;

FIG. 3 is a rear view thereof;

FIG. 4 is a left side view thereof;

FIG. 5 is a right side view thereof;

FIG. 6 is a top plan view thereof;

FIG. 7 is a bottom plan view thereof; and,

FIG. 8 is a rear perspective view thereof.
